UNITED STATES PATENT OFFICE.

ACHILL BIPPART, OF NEWARK, NEW JERSEY.

DESIGN FOR A SAFETY-PIN.

SPECIFICATION forming part of Design No. 30,390, dated March 28, 1899.

Application filed January 16, 1899. Serial No. 702,367. Term of patent 7 years.

To all whom it may concern:

Be it known that I, ACHILL BIPPART, a citizen of the United States, residing at Newark, county of Essex, State of New Jersey, have 30
invented a certain new and useful Design for
a Safety-Pin, fully described and represented
in the following specification and the accompanying drawings, forming a part of the same.

Figure 1 is a side view of the safety-pin embodying my design. Fig. 2 is a front view of the pin. Fig. 3 is a rear view of the pin. Fig. 4 is a section on line 5 5 in Fig. 1, looking toward the tongue; and Fig. 5 is an end view of the hinge-joint.

As shown in the drawings, the leading or material features of my design are the form of the body, comprising a double-ribbed bar, the quadruple coils forming the hinge-joint, and a forked connection of the tongue with the two outer coils.

A designates the body, consisting of a single bar with straight parallel edges and exhibiting upon the outer side two parallel ribs of rounded contour. The body has at one end the usual pin-guard A' and at the opposite end two central coils B upon a line with the

body and two lateral coils B', projecting equally upon the opposite sides of the body and connected with the tongue C by the fork C'.

The essential features of the design are the body comprising the bar, with two rounded ribs, the coils B upon a line with the body, the coils B', projected equally at opposite sides outside the line of the body, and the fork connection of the tongue with the two outer coils.

It is apparent that this design is applicable to safety-pins with a jewel setting upon the front side of the body A.

Having described my design, what I claim as new, and desire to secure by Letters Patent, is—

The design for a safety-pin as herein shown and described.

In testimony whereof I have hereunto set my hand in the presence of two subscribing witnesses.

ACHILL BIPPART.

Witnesses:

JOHN G. BEACH,
THOMAS S. CRANE.
